H. B. WALTER

BOX

Filed March 15, 1922

FIG. 1.

FIG. 2.

FIG. 3.

FIG. 4.

Inventor
Harrison B. Walter
By Clarice E. Melhope
Attest.

UNITED STATES PATENT OFFICE.

HARRISON B. WALTER, OF CHICAGO, ILLINOIS, ASSIGNOR TO CHICAGO MILL AND LUMBER COMPANY, OF CHICAGO, ILLINOIS, A CORPORATION OF ILLINOIS.

BOX.

Application filed March 15, 1922. Serial No. 543,837.

To all whom it may concern:

Be it known that I, HARRISON B. WALTER, a citizen of the United States, and a resident of Chicago, county of Cook, and State 5 of Illinois, have invented certain new and useful Improvements in Boxes; and I do hereby declare that the following is a full, clear, and exact description thereof, reference being had to the accompanying drawings, and to the letters of reference marked thereon, which form a part of this specification.

This invention relates to improvements 10 in boxes of fibre or paper board and consists of the matters hereinafter described and more particularly pointed out in the appended claims.

The invention relates more particularly to 15 the type of collapsible box which is set up for packing with one end attached to the body and the other end open and consists of an elongated mat or blank creased to be folded to form a tubular body and capable of being collapsed upon itself; and of separate end parts, which may be included with 20 the collapsed body in a flat package when supplied to the user or packer. The general type of box is shown in Letters Patent heretofore granted to me, No. 1,055,243, dated March 4th, 1913, and No. 1,125,782, dated January 19, 1915.

The object of the present invention is to 25 provide certain novel and improved features in a box of the kind whereby its strength and resistance to rough handling is greatly increased. This and other advantages of the invention will be more particularly pointed out as I proceed with my specification.

40 In the drawings:—

Figure 1 is a perspective view of the improved box as it appears when set up and packed ready for shipping;

Figure 2 represents an end elevation of 45 the box;

Figure 3 is a view representing, on an enlarged scale, a partial section through the top wall and one end wall, in a plane indicated by the line 3—3 of Figure 2;

Figure 4 is a view representing on a like scale, a partial horizontal section through one side wall and an end wall, in a plane indicated by the line 4—4 of Figure 2;

55 Figure 5 is a plan view representing the

parts comprising an end wall assembled in the relation they occupy when applied to the box.

Referring now to that embodiment of the invention illustrated in the drawings:—10 60 indicates the body of the box. This is a rectangular tube, open at its ends, with two narrow sides 11, 11 and two wider sides 12, 12,—one of the narrow sides, in the example illustrated, being provided with a 65 narrow, lateral flap extension 13, which is attached to the proximate side 12 by means of staples or in any other convenient manner. The said body is made from a mat or blank of heavy fibre or paper board 70 which is creased along parallel lines spaced at the required distances to define the several sides of the box body and the flap extension 13. The said creases permit the mat or blank to be folded into box form 75 when it is set up for use and to be collapsed upon itself when the boxes are shipped to the user in a stack of flat packages, in a well-known manner.

14 indicates the end members of the box. 80 These each consist of two pieces 15, 16 shown in plan in Figure 5. The piece 15 is made of the internal cross-sectional area of the box, with the addition of flange extensions 15^a, 15^a at its sides defined by 85 creases 15^b, 15^b. The piece 16 is of a like area, with the addition of flange extensions 16^a, 16^a defined by creases 16^b, 16^b. The two pieces are so cut from the mats or strips from which they are made, with reference 90 to the direction in which their flanges extend, that when placed one upon the other as shown in Fig. 5, with the flange extensions located on all sides of the combination presented by the two, the grain of the fibre 95 or paper board in one piece will extend at an angle, preferably a right angle, to the grain of the other.

The two pieces are secured in an end of the tubular body in the assembled relation 100 just described, with the several flange extensions attached to the inside parts of said sides by means of staples or otherwise (see Figures 3 and 4) as in the case of the single piece end parts of the boxes shown in the 105 patents hereinbefore referred to. One end is applied as soon as the body is set up and the other end is applied after the box has been packed.

The two piece construction of the ends of 110

the box makes a very strong and rigid structure, capable of greatly increased resistance to breakage or deformation, due to rough handling. This strength is further added to by the arrangement of the two pieces comprising the end closure, with the grain of one piece running at an angle to the grain of the other piece,—the relative weakness of the one piece in one direction being manifestly reinforced by the relative strength of the other piece in that direction.

Another advantage of the improved box lies in the fact that the pieces comprising the ends may be produced at considerable saving in labor, as compared to a box with ends consisting of single pieces, since each piece may be cut and creased from a continuously fed strip and it is not required to again handle the piece to notch the corners as in the case of the single piece end closures.

I claim as my invention:—

1. In a box of the kind described, in combination with a tubular body, an end closure for said body comprising two pieces, each piece including a main part having an area substantially equal to the cross-sectional area of the tubular body and having flange extensions upon two opposite sides capable of being folded at right angles to the plane of the piece and having no extensions on its other sides, the two pieces being

adapted to be inserted, with the main part of one flat against the main part of the other, in the open end of the tubular body, 35 and with the flange extensions of one piece disposed at right angles to the flange extensions of the other piece.

2. In a box of the kind described, in combination with a tubular body, an end closure 40 for said body comprising two pieces, each piece including a main part having an area substantially equal to the cross-sectional area of the tubular body and having flange extensions upon two opposite sides capable of 45 being folded at right angles to the plane of the piece and having no extensions on its other sides, the two pieces being adapted to be inserted, with the main part of one flat against the main part of the other, in 50 the open end of the tubular body, with the flange extensions of one piece disposed at right angles to the flange extensions of the other piece, and with the grain of the one piece running at an angle to the grain of the 55 other piece.

In testimony that I claim the foregoing as my invention, I affix my signature in the presence of two witnesses, this 7th day of March, A. D. 1922.

HARRISON B. WALTER.
